A.-G., OF OELDE, GERMANY.

CENTRIFUGAL DOME WITH CONDENSING ARRANGEMENT

Application filed October 3, 1928, Serial No. 310,148, and in Germany September 10, 1927.

Liquids, separating, during discharge from the centrifugal-drum vapours of moist gases, evaporate easily, or are forming foam in the catch-chambers and drains of the dome of the 5 centrifugal, which can not be drawn-off from the usual centrifugal-domes, divided into catch-chambers, without causing the disadvantage, that the produced foam-, or vapour-bubbles escape into the air-space surrounding the centrifugal and are lost. If the loss 10 of the condensate from vapours and foam is for once important in an economical respect, attention to the separator and working in its vicinity besides rendered difficult consequent to the molestation and contamination 15 caused by the said separation and directly made impossible in the case of corrosive vapours. On the other hand, the danger, that explosive mixtures are being formed by the 20 gases escaping from the separator, must at all events be avoided. Vapour-fogs are generally penetrating into the separator-frame and exert a noxious influence upon the bearings. In the case of some liquids, quite an undesirable 25 concentration of the material worked by the centrifugal is produced by the lost condensates of valuable diluting-admixtures.

The catch-chambers, drain-pipes and adjacent receptacles are filled, under excessive formation of foam, to such an extent with foam, 30 that a regular discharge is prevented and the capacity of the centrifugal can not be fully utilized.

It is generally endeavoured to eliminate 35 these drawbacks thereby, that the dome of the centrifugal is closed up air-tight and connected by pipe-lines with equally tight receiving-vessels. This means however, that large space, an expensive plant and cost of maintenance are required and a special condensing-plant has to be installed besides. The 40 unavoidable pipe-packings give likewise always cause for troubles.

The present invention offers an extraordinary simple arrangement for condensing moist gases and foam within the centrifugal.

For this purpose, a plate or partition has been provided, forming between the cover 45 or roof of the centrifugal an intermediate

space, connected with the lower catch-basin or chamber.

The stream of liquid, and the gas-stream, are conducted in opposite directions towards the desired zones. 55

The catch-chamber can be provided with an outlet fitted with a hydraulic closure for aiding the said arrangement.

The suction-effect of the escaping liquid-stream in the catch-chamber is being supported by the pressure produced at the periphery of the catch-basin consequent to the hydraulic closure. The vapours will therefore pass easier over the screen, as if the hydraulic closure would be missing. 65

The arrangement is illustrated in the drawing by way of an example, wherein

Figure 1 shows the arrangement with hydraulic closure, and

Figure 2 without the same. 70

Figure 3 illustrates a modified form, in which the cover of the catch-chamber is replaced by the roof of the centrifugal.

Figure 4 shows an arrangement, being a combination of Figs. 1 and 3. 75

According to the embodiment of my invention, shown in Figure 1, the housing comprises a circular base frame 1 provided with an annular bearing support 2 and an upper cylindrical section 3 provided with a discharge spout 4 and an overflow spout 5. A rotary drum 6 mounted on a vertical shaft 7 journalled in the bearing support 2, is provided with a frusto-conical upper portion 8 which merges into a cylindrical nozzle 9 provided with discharge outlets 10. A cylindrical partition wall 11 has a frusto-conical upper portion 12 contracted upwardly around and below the nozzle 9. The section 3 of the cylindrical housing is formed with a catch chamber for collecting the fluid discharging from the discharge outlets 10. Mounted within the housing section 3 is a circular dome 13 which is contracted upwardly around a reduced cylindrical portion 14 and above the discharge outlets of said rotor nozzle. An upwardly contracted annular passage or channel 15 is provided between the under surface of the circular dome 13 and the upper surface of a curved segmental baffle plate 16 90

which terminates above the nozzle 9 but has its upper edge separated therefrom by an annular space 17. A cylindrical receptacle 18 for the fluid to be charged into the centrifugal, is connected by a tubular conductor 19 to the upper end of the centrifugal.

According to Figure 2 of the drawings, the annular space 30 into which the centrifugal discharges, communicates through a downwardly-presented annular opening 31 with a catch chamber 32, the baffle or partition 33 being provided with a depending extension 34 for this purpose.

As the fluid is thrown outwardly from nozzle 9 against the inner surface of baffle plate 16, an injector-like action is produced on the restricted outlet of separator channel 15, while at the same time the lighter or bubble-containing portions of the fluid are displaced upwardly through the catch chamber toward the enlarged inlet opening of said channel 15 by means of the heavier liquid below. These combined pressure and suction effects produce a rapid and effective separation of the gaseous portions from the liquid and a flow of said gaseous portions upwardly through the channel 15 towards the axis of the rotor.

The thrown off liquid, jumps together with the partly enclosed, partly in form of vapour or foam carried along separated liquid-bubbles, over to the catch-chamber at the lower opening of the annular canal.

The vapours rise therefore from below into the intermediate space between the dome and baffle-plates and are carried downward, at the lower free opening, by the injector-like action of the material discharged from the centrifugal. By this jumping over of the liquid-bubbles to the catch-chamber, the lower canal-opening is closed by a liquid-film, from which the upwards moving gas-bubbles are deflected by the current produced in the canal, or are being sucked through the liquid-film. Some of the bubbles have been condensed during their progress toward the catch-chamber while the gaseous constituents rising into the channel 15, are sucked into the annular chamber between the baffle-plate and the dome 14, and are entrained by the upwardly moving fluid in the annular channel to be ejected above.

The condensate is retained in the material, leaving the catch-chamber of the centrifugal free from gas and foam.

As explained above, a suction-effect is to be obtained by the escaping-liquid-stream.

This suction-effect is however supported by a hydraulic-closure, which latter produces a pressure at the periphery of the catch-basin, therefore causing an accumulation of the gas-separation in the chambers, whereby the gases are imported a surplus-pressure and consequently more easily driven into the separator channel and from thence forced into the liquid-space, wherein they are condensed.

According to the embodiment of my invention shown in Figure 3, the cover 20 of the upper housing section forms one wall of the separator channel 21, the other wall of said channel being formed by the partition wall 76 or baffle-plate 22 which is provided with a depending cylindrical wall or extension 23.

In the embodiment of my invention shown in Figure 4, an upper catch-chamber 24 of greatly reduced diameter, is provided. In this form of my centrifugal, an annular channel 25 is formed above the baffle or partition 26, the bottom wall 27 of the upper catch-chamber 24 being extended over the annular space at the top of baffle 26.

The advantage of the arrangement consists therein, that the annular canal for the return-flow of the vapours has become very large and that the upper and side-walls strike the outer atmosphere directly, so that a certain cooling takes place at this point, whereby condensation is favourably influenced.

I claim:

1. In a centrifugal separator, the combination of a housing provided with a catch-chamber, a centrifugal rotor mounted within said housing and provided with a nozzle discharging into said catch-chamber, the bottom wall of said catch-chamber being contracted upwardly around and below said nozzle, a baffle-plate forming the top-wall of said catch-chamber, said baffle-plate being contracted upwardly around and above said nozzle, a partition wall arranged above said baffle-plate and suitably disposed with respect thereto to form an upwardly and inwardly contracted channel, said baffle-plate being provided with an opening into said catch-chamber and above said nozzle, the channel being thereby adapted to discharge into said catch-chamber under the suction created by the nozzle discharge.

2. In a centrifugal separator, the combination of a housing having a catch-chamber discharging outwardly and in communication with the larger lower end of an upwardly and inwardly contracted channel, a centrifugal rotor discharging radially outward into said catch-chamber, said catch-chamber being in communication with the contracted upper end of said upwardly and inwardly contracted channel by an opening adjacent to and above the discharge outlet of said centrifugal rotor, said inwardly and upwardly contracted channel being provided with a closed top wall.

3. In a centrifugal separator, the combination of a housing having a catch-chamber discharging outwardly and in communication with the larger lower end of an upwardly and inwardly contracted channel, a centrifugal rotor discharging radially outward into said catch-chamber, said catch-chamber being in communication with the contracted upper end of said upwardly and inwardly contract-

ed channel by an opening adjacent to and above the discharge outlet of said centrifugal rotor, said inwardly and upwardly contracted channel being provided with a closed top 5 wall, said discharge outlet of the centrifugal rotor being arranged to discharge across the communicating opening between said upwardly and inwardly contracted channel and said catch-chamber whereby the foam and 10 bubbles in the treated fluid are condensed under the combined suction and injector action thus produced.

4. In a centrifugal separator, the combination of a housing having a catch-chamber and 15 an upwardly and inwardly contracted annular channel arranged above and opening downwardly into said catch-chamber at the enlarged lower end of said annular channel and a centrifugal rotor mounted on a vertical 20 axis within said housing and provided with a radial discharge nozzle below the contracted upper end of said annular channel, said contracted upper end of the annular channel being in open communication with the inner upper 25 end of said catch-chamber above said discharge-nozzle of the rotor.

5. In a centrifugal separator, the combination of a housing, a centrifugal rotor mounted on a vertical axis within said housing and provided with a discharge nozzle 30 above, said housing having a closed wall contracted upwardly around and below said nozzle, and forming the bottom wall of a catch-chamber, a baffle-plate contracted upward- 35 ly toward the axis of said rotor and extending above the discharge nozzle therein, said baffle-plate forming the top wall of said catch-chamber, and a closed dome-like partition plate arranged above said baffle-plate and 40 forming therewith an upwardly and inwardly contracted channel, said baffle-plate being provided with an annular opening extending around said nozzle and above the discharge outlets therein, the contracted upper end of 45 said upwardly and inwardly contracted channel being thereby adapted to discharge into the upper end of said catch-chamber under a combined injector action and suction.

6. In a centrifugal separator, the combination with a housing and a centrifugal rotor journalled in said housing and provided with discharge openings, said housing including a catch-chamber having closed top and bottom walls and a discharge outlet closed by a 50 hydraulic seal, a third closed wall in said housing which forms with the closed top wall of said catch-chamber an upwardly contracted annular channel having its contracted upper end extending around and above said 55 discharge openings in the rotor, the contracted upper end of said annular channel opening downwardly into the upper part of said catch-chamber.

In testimony whereof I affix my signature.
CARL SCHMITZ.
